14 Claims. (Cl. 252--175)

1

This invention relates to agglomerated meta- or polyphosphates containing sodium carbonate and/or a wetting agent and to a process for making same.

An object of the invention is to provide a process for making an agglomerate of the above type in the form of a cube or other suitable configuration containing a predetermined number of water softening units and having an increased solution rate.

Another object of the invention is to provide a process for producing an agglomerated water treating composition including a wetting agent, sodium hexametaphosphate or a sodium polyphosphate and a sufficient amount of hydrated sodium carbonate to furnish a strong but readily soluble product which will furnish a hydrogen ion concentration in water within the preferred range for efficient detergency.

Another object is to provide a process for making agglomerated meta- or polyphosphates containing a wetting agent, wherein an accurate control is maintained over the amount of water added to form the agglomerates.

A further object is to provide a process for making agglomerated meta- or polyphosphates containing a wetting agent and sodium carbonate wherein the rate at which the water is released during the agglomerating operation is temperature controlled to give more uniform agglomeration.

A still further object is to provide a process for making agglomerates of the above type wherein the distribution of water throughout the agglomerated mass is uniform.

An additional object is to provide a process for making agglomerated meta- or polyphosphates containing sodium carbonate and a wetting agent, which process yields uniformly sized agglomerates containing only very small quantities of fines and oversize.

Other objects will be apparent to those skilled in the art as the description proceeds.

One of the difficulties attending the solution in water of the alkali metal meta- or polyphosphates is the tendency of such phosphates when added to water to become sticky and gummy and form a very viscous solution immediately in contact with the surface of said phosphates with the result that diffusion through the film is very slow and the solution process is time consuming. It has already been proposed to increase the solution rate of metaphosphates by pressing them into thin flakes and coating the flakes with alkali metal salts. This treatment improves the

2

solution rate of the metaphosphates over that of the original material, but in most instances the rate is still so slow as to be objectionable for many purposes.

In addition to the slow solution rate, the flaked metaphosphates have the objectionable property of having a tendency to stick to or cut the hands. Such a product also has the disadvantage that in use it is difficult to gauge the amount of material necessary to soften a given quantity of hard water with the result that the consumer must resort to the wasteful practice of adding more than is necessary in order to be certain of obtaining the desired result.

One of the difficulties in agglomerating meta- or polyphosphates is the fact that such phosphates, when in contact with water or water vapor, tend to acquire a sticky or gummy consistency which adds to the difficulties of mechanically controlling and handling such moist products. After these phosphates become sticky and gummy there is great difficulty in uniformly distributing the moisture throughout the agglomerates and also in uniformly proportioning loose salt mixtures containing such sticky phosphates with the result that granules tend, during manufacture, to become non-uniform in composition.

I have now found that if the moisture required for the agglomeration of these phosphates or mixtures containing same is incorporated in the form of an efflorescent hydrated salt such as hydrated sodium carbonate and if a wetting agent is employed in the agglomerating operation, I obtain a product which is uniform as to size, chemical composition and water content. My product also has a relatively high solution rate as compared with the products of the prior art and it has none of the objectionable properties of flaked metaphosphates or the other forms of metaphosphates and polyphosphates. It is self-dissolving, that is, it requires no agitation to dissolve it in water and when made into various shapes such as cubes, tablets, etc. containing a predetermined number of water softening units, it is in a very convenient form for domestic use since the consumer does not have to guess at the amount of material required to give the desired result. My invention, therefore, contemplates the formation of cubes, tablets, etc. of agglomerates in different sizes containing a predetermined number of water softening units to accommodate waters of varying degrees of hardness and also different volumes of water of the same degree of hardness such as used in the

home in bath tubs, laundry tubs, dish pans, wash pans and the like.

By water softening units I mean calcium and/or magnesium reversion values, which values will be controlled not only by the size of the cubes, tablets, etc. but also by the relative proportions of the phosphate and sodium carbonate contained therein.

I have discovered, for example, when producing agglomerates of sodium metaphosphate and sodium carbonate, that I may employ the sodium carbonate in whole or in part as a hydrate lower in water content than the fully hydrated salt. For example, I have found that a mixture of hydrates of sodium carbonate containing say 15 from 30% to 40% of water of hydration may be intimately mixed with the ground hygroscopic metaphosphate and that then the rate of transfer of water from the hydrated salt to the metaphosphate is slow enough to permit intimate thorough mixing of the constituents before the development of a sticky condition takes place. The rate and the amount of water released from the hydrated salt employed for agglomeration can be controlled by varying the degree of hydration of the hydrated salt and also by the temperature at which agglomeration is carried out and, therefore, the process may be adapted to straight line continuous agglomeration. Accordingly at no time is there sufficient water vapor present in contact with the phosphate that serious reversion may take place.

In contrast to this method, the older methods usually provide for a spray of liquid water or exposure of the agglomerating constituents to humidified air under which conditions the more hygroscopic materials in the mixture have the tendency to acquire an excess of or more than their share of water. Since the hygroscopic constituent is the metaphosphate (or polyphosphate) there was danger that the moist metaphosphate containing an excess of water would, in part at least, revert to the orthophosphate. There was also, as a result of the older process, the tendency of certain parts of the agglomerating mixture to become too moist and consequently produce over-size material, while other parts of the mixture did not receive enough water to give satisfactory agglomeration and the development of sufficient strength to prevent shattering of the granule during handling.

The metaphosphates and polyphosphates treated in accordance with the present invention are compositions which contain varying ratios of Na_2O and P_2O_5 . They are ordinarily prepared by heating together either the corresponding orthophosphates or by heating together orthophosphoric acid and a sodium salt such as soda ash, Na_2CO_3 . Such products are commonly termed molecularly dehydrated phosphates. The temperature to which the starting materials are heated is carried up to the sintering or reaction temperature and usually to the temperature at which complete fusion is obtained. When complete fusion is obtained, the melt is congealed by quickly cooling the molten mass. The character of the resulting solid depends somewhat upon the ratio of Na_2O to P_2O_5 employed in the starting products. Where the mol ratio of Na_2O to P_2O_5 is 1:2, (17.9% Na_2O and 82.1% P_2O_5 by weight) or even as high as 3:2, the product obtained is generally a clear, glassy, brittle, non-crystalline solid. When the product is as high in alkali as the 5:3 ratio, a crystalline phase manifests it-

self by the development of translucency in the glassy matrix.

When preparing Graham's salt, ordinarily designated as sodium hexametaphosphate, $(\text{NaPO}_3)_6$, or compositions containing the same, it is desirable to heat the ingredients entering into the reaction to the fusion temperature and then quickly cool the melt in order to obtain the metaphosphate not only in the water soluble form but also in a form in which it will most efficiently act as a water softening agent.

The metaphosphate containing composition treated in accordance with this invention may have either a higher or a lower Na_2O content than that corresponding to NaPO_3 . Lower ratios may include the Na_2O to P_2O_5 ratio of 1:2 (where the composition comprises sodium metaphosphate together with metaphosphoric acid, HPO_3). These lower ratios are also glass-like, brittle solids and are somewhat more hygroscopic than the higher ratios. Other ratios include sodium metaphosphate itself (NaPO_3) or $(\text{NaPO}_3)_6$, i. e., where the ratios are 1:1 and range upwardly including the following additional specific compositions:

Composition Equivalent to the Formula:	Ratio $\text{Na}_2\text{O}:\text{P}_2\text{O}_5$	Weight Na_2O	Per Cent P_2O_5
$\text{Na}_{12}\text{P}_{10}\text{O}_{31}$	6.5	34.4	65.6
$\text{Na}_8\text{P}_4\text{O}_{13}$	3.2	39.6	60.4
$\text{Na}_5\text{P}_3\text{O}_{10}$	5.3	48.0	52.0

Mixtures of the above compounds may likewise be treated.

When the compositions are obtained as solid, glassy compositions, the brittle glass is readily ground to a fine powder, preferably of such a size as to pass through an 80 mesh screen. The powdered glass is then treated by the herein described process.

Broadly stated, my process comprises mixing together an efflorescent salt hydrate, a wetting agent and a finely divided powder comprising a molecularly dehydrated alkali metal phosphate having an alkali metal oxide/ P_2O_5 ratio substantially in the range of from 1:2 to 5:3 and agitating the mixture to form agglomerates.

More particularly, my process involves mixing together an alkylated aromatic sulfonate or sulfate, hydrated sodium carbonate and a finely divided molecularly dehydrated sodium phosphate having a $\text{Na}_2\text{O}/\text{P}_2\text{O}_5$ ratio of from 1:1 to 5:3 and agitating the mixture to form agglomerates.

Still more particularly, my process involves mixing together hydrated sodium carbonate having between 30% and 40% water of crystallization, sodium lauryl sulfate and a finely divided molecularly dehydrated sodium phosphate having a $\text{Na}_2\text{O}/\text{P}_2\text{O}_5$ ratio from 1:2 to 1:1, agitating the mixture to form agglomerates, forming a layer of the agglomerates upon a suitable surface, sintering the layer of agglomerates to form a unitary sheet, subdividing the sheet by any suitable means into a plurality of detachable sections containing a predetermined number of water softening units and drying the product.

My invention is illustrated but not limited by the following examples:

Example 1

Applying my discovery to the agglomeration of sodium hexametaphosphate (the preferred embodiment) I proceed in the following manner:

One part by weight of a wetting agent such as

a sodium salt of an alkylated aromatic sulfonic acid containing 8 to 16 carbon atoms in the alkyl chain is dissolved in 5 parts of water. This solution is added to 9 parts of dry soda ash and stirred until the mix begins to granulate and dry out. This operation yields about 14 parts by weight of a hydrated soda ash

containing about 1 part by weight of the above wetting agent. The product is intimately mixed with 90 parts by weight of -80 mesh ground sodium hexametaphosphate. This intimate mixture remains dry for from 1 to 5 minutes after mixing when the temperature is between 10° and 30° C. The intimate mixture of the phosphate, wetting agent and carbonate is now passed through a rotating drum and in about 3 to 5 minutes after mixing agglomeration will start due to the release of water from the hydrated salt. The degree of agglomeration can be controlled by the length of time the salt mixture is tumbled in the rotating drum, a longer time of tumbling producing a larger agglomerate. If low bulk density, softer agglomerates are desired, the agglomerating action is continued until the desired size range (usually -10+30 mesh) is obtained. If a hard dense product is desired, the salt mixture after mixing is allowed to stand without agitation for from 5 to 10 minutes. The hydration of the phosphate takes place in the quiescent mass. The somewhat sticky mass is then mechanically shredded and passed into a rotary agglomerator or revolving drum and the particles rounded by the tumbling action within the drum.

The agglomerates made by either method are then removed from the agglomerator and dried by exposure to warm air. The products thus formed are very free flowing, and when dissolved in water to form a 1% solution, they give a pH of about 8.2 which is within the range (8.0-9.0) desired for domestic detergent purposes.

The products produced by the above process have substantially the following chemical composition:

	Per cent
Sodium hexametaphosphate	90
Sodium carbonate	9
Sodium salt of an alkylated aromatic sulfonic acid containing 8 to 16 atoms in the alkyl chain	1

While the above agglomerates constitute a very satisfactory product, it is desirable from the standpoint of domestic use to prepare them in a form containing a predetermined number of water softening units. This may be accomplished by molding or tableting the moist agglomerates discharged from the agglomerator and drying the product.

Another method of accomplishing the same result consists in discharging the moist agglomerates onto a suitable surface in the form of a layer of substantially uniform thickness, heating the layer to form a unitary sheet, subdividing the sheet into detachable sections by forming grooves into the surface of the sheet and then drying said sheet. As a modification of this procedure, the sheet may be cut into cubes or tablets and then dried.

Considerable care should be used in these operations to avoid either compressing the agglomerates too strongly or forming a layer that is too thick, otherwise it will be difficult to uniformly dry the product. If the product is not properly

dried, reversion will take place with the result that its water softening capacity will be substantially reduced.

The agglomerate layer may vary in thickness, but for most satisfactory results, I prefer to use a layer of not greater than one quarter of an inch.

Example 2

12.5 parts of hydrated sodium carbonate

containing 0.5 part by weight of added sodium lauryl sulfate is prepared by the procedure set forth in Example 1, using 4 parts by weight of water. This product is thoroughly mixed with 91 parts of -80 mesh ground sodium hexametaphosphate in a pug mill or rotating drum. The mix becomes tacky in one to three minutes and after continued stirring or agitation, agglomeration of the hexametaphosphate takes place. The wet agglomerates are removed and forced through a 12 mesh screen. The screened agglomerates are then dried in $\frac{1}{4}$ " deep layers for 30 to 40 minutes with circulating air at 80° C. to 90° C. The dried agglomerates are rescreened and a yield of 90-95% of -12+30 mesh agglomerates is thus obtained.

Prior to drying, the agglomerates obtained by the above process have the following composition:

	Per cent
Sodium hexametaphosphate	87.50
Sodium carbonate, hydrated	12.02
Sodium lauryl sulfate	0.48

After drying, the agglomerates have the following composition:

	Per cent
Sodium hexametaphosphate	91.0
Sodium carbonate	8.5
Sodium lauryl sulfate	0.5

If desired, the moist agglomerates may be treated as in Example 1 to form cubes, tablets, etc., containing a predetermined number of water softening units.

Example 3

15 parts of hydrated sodium carbonate,

containing 2 parts by weight of dodecyl benzene sodium sulfonate is prepared by dissolving 2 parts of said sulfonate in 6 parts of water, adding the solution thus formed to 9 parts by weight of dry soda ash and stirring until the mix begins to granulate and dry out. The resulting product is intimately mixed with 89 parts by weight of -80 mesh ground sodium hexametaphosphate in a pug mill, rotating drum or other suitable mixing or agitating device and is then treated as in Example 2 above.

The dried product made by the process described in Example 3 has substantially the following composition:

	Percent
Sodium hexametaphosphate	89
Sodium carbonate	9
Dodecyl benzene sodium sulfonate	2

Example 4

Approximately 0.6 part by weight of a sodium alkyl benzene sulfonate consisting of a mixture of sulfonated compounds derived from the alkylation of benzene by a kerosene boiling within the range of 190° to 230° C. is dissolved in 23.7 parts of

water and the resulting solution is stirred with 55.3 parts of dry soda ash until the ash begins to granulate and dry out. The product consisting of 79 parts of hydrated soda ash containing approximately 30% water of hydration and 0.6 part by weight of the above wetting agent is intimately mixed with 546 parts of a -80 mesh phosphate composition comprising 76% by weight of sodium hexametaphosphate, 8% by weight of sodium acid pyrophosphate and 16% by weight of tetrasodium pyrophosphate. The mixture thus formed is treated as in Example 2 above to produce a dry free flowing product having the following composition:

	Per cent
Phosphate composition	90.71
Sodium carbonate	9.18
Sodium alkyl benzene sulfonate	0.10

Example 5

1.2 parts by weight of sodium oleyl sulfate is dissolved in 29.0 parts of water and to this solution 54.00 parts of anhydrous sodium carbonate is added with stirring. The stirring is continued until the carbonate begin to granulate and dry out and the product consisting of 83 parts of hydrated sodium carbonate ($\text{Na}_2\text{CO}_3 \cdot 35\% \text{H}_2\text{O}$) and 1.2 parts by weight of the above wetting agent is intimately mixed with 546 parts of a -80 mesh phosphate powder having the same composition as that described in Example 4. The mixture is then treated as in Example 1 to form a dry product having the following composition:

	Per cent
Phosphate composition	90.82
Sodium carbonate	8.97
Sodium oleyl sulfate	0.20

The agglomerates produced in Examples 3, 4 and 5 may be molded or otherwise shaped into cubes, tablets, etc., of various sizes containing a definite number of water softening units.

When dropped into water the above described products sink a short distance and then the carbon dioxide liberated circulates and floats them within the body of the liquid until they reach the top where the gas is released and then the cycle is repeated until solution takes place.

This behavior on the part of the agglomerates is attributed to the presence therein of a small amount of a wetting agent which causes the carbon dioxide to be released slowly and uniformly. The slowly liberated CO_2 floats the agglomerates and sets up convection currents which circulate them within the body of the liquid. This has the desirable effect of continuously exposing the agglomerates to the dissolving action of substantially pure water or water containing only relatively small concentrations of dissolved phosphates. As a result of this action, the agglomerates dissolve very rapidly and completely and they do not form a viscous solution immediately adjacent their surfaces and thereby retard the solution rate of the undissolved material as is the case of prior art materials which do not contain a wetting agent.

The rate and amount of carbon dioxide developed by the agglomerates may be controlled to meet specific requirements by varying the amount of the sodium carbonate and wetting agent in the product. The pH and the calcium repression values of my product can be controlled by varying the proportions of phosphates and sodium carbonate with respect to each other.

The chemical composition of the agglomerated

product may vary considerably, but it is not desirable to use larger or smaller quantities than that indicated in the following formulation:

	Per cent by weight
5 Phosphate composition	86-91
Sodium carbonate	7-12
Wetting agent	0.1-2

If larger or smaller quantities than that indicated above are employed, there is obtained either a product which furnishes a hydrogen ion concentration in water outside the preferred range for efficient detergency or a product having a decreased water softening capacity due to the dilution effect.

By phosphate composition, I include alkali metal hexametaphosphates, alkali metal polyphosphates or any of the molecularly dehydrated alkali metal phosphates or phosphate mixtures described herein.

I obtain the most satisfactory results from the standpoint of detergent and water softening action by employing an agglomerated product having the following composition:

	Per cent
Sodium hexametaphosphate	89
Sodium carbonate	10
Wetting agent	1

It will be noted that in describing my process I have pointed out that the wetting agent is dissolved in water, that the solution thus formed is added to anhydrous sodium carbonate and that the hydrated salt thereby obtained is mixed with the meta- or polyphosphate. This is the preferred method of carrying out my process as a more effective distribution of the wetting agent is thus obtained with the result that the wetting agent exercises a more effective control over the development of CO_2 by the product. However, it should be understood that the wetting agent may be added to the meta- or polyphosphate and then mixed with the hydrated salt; it may be added to the hydrated salt and then combined with the meta- or polyphosphates or it may be simultaneously mixed with the other two constituents. In fact, it may even be applied as a coating to the agglomerated product, but this method is objectionable because it requires large amounts of wetting agents (about 5% by weight) which dilute and thereby decrease the water softening capacity of the product to an undesirable degree.

Water soluble alkali metal alkyl sulfates, alkylated aromatic sulfonates and alkali metal salts of the higher fatty acids generally are suitable wetting agents. The sodium salts of sulfonated or sulfated alcohols containing 12 or more carbon atoms give very satisfactory results, but I prefer to use the water soluble salts of alkylated aromatic hydrocarbon sulfonic acids, particularly the alkali metal salts of alkylated benzene sulfonic acids in which at least one alkyl group contains from 11 to 15 carbon atoms and mixtures thereof. Such salts of alkylated aromatic hydrocarbon sulfonic acids are described in Patent No. 2,161,174 to Kyrides. Alkali metal salts of sulfonic acids of undecyl, dodecyl, tridecyl, tetradecyl and pentadecyl substituted benzene, toluene, xylene and similar aromatic hydrocarbons of the benzene series, as well as their isomers and mixtures thereof, are included within the ambit of my invention.

The above wetting agents are merely illustrative of the preferred types of compounds and it should

be understood that any suitable wetting agent may be employed in my process.

As indicated above, the wetting agent is preferably employed in amounts ranging from 0.1% to 2% by weight of my agglomerated product, but it is within the scope of my invention to employ larger or smaller amounts if desired.

While the use of the mixed hydrates of sodium carbonate containing about 35% H_2O is preferred, other hydrates either alone or mixed so as to approximate a water content of from 30 to 40% may be employed. For example, mixtures of the monohydrate and the decahydrate approximating a water content of from 35% to 40% or mixtures of the anhydrous salt and the decahydrate may also be used.

In general, in the agglomeration of meta- and polyphosphates having a particle size of less than 80 mesh, the hydrated Na_2CO_3 should be adjusted in amount and water content so as to furnish from 3 to 6% by weight of water in the mixture to be agglomerated.

For the purpose of modifying somewhat the properties of the agglomerate for treating various waters, it is possible to incorporate other salts, or hydrates thereof, together with the sodium carbonate hydrate. Should it, for example, be desired to supply sulfate, orthophosphate or pyrophosphate ion to the treated water, it is possible to incorporate into the agglomerate, sodium sulfate, sodium orthophosphate or sodium pyrophosphate as a constituent thereof. When hydrates of these salts are employed, they may be employed in lieu of the hydrates of sodium carbonate or in combination with anhydrous sodium carbonate.

The mechanism by which my agglomerates are formed comprises first a loss of water of hydration of the hydrated salt, which water is then absorbed by the adjacent molecularly dehydrated phosphate particles with the formation of a sticky film on such particles. The agglomerate is then formed by the mechanical action of mixing or rolling the particles of salts over each other in the drum. Thus it will be noted that the moisture transference takes place at a uniform rate and to a uniform degree throughout the mass of particles.

The agglomerated product prepared in accordance with the present invention comprises distinct highly porous granules composed of irregularly shaped powder particles of phosphate salts loosely adhering to each other. These granules have intimately and uniformly interspersed therein a wetting agent and a sodium salt selected from the group consisting of sodium carbonate, sodium sulfate, sodium orthophosphate and sodium pyrophosphate and each granule is characterized by having a substantially higher rate of solution than a physical mixture of its components.

This application is a continuation-in-part of my copending application, Serial No. 497,141, filed March 13, 1943 now Patent No. 2,414,969 issued on January 23, 1947.

While I have specifically described the preferred embodiments of my invention, it is to be understood that the invention is not so limited, but may be otherwise embodied and practiced within the scope of the following claims.

What I claim is:

1. A water treating product in the form of distinct highly porous agglomerates consisting essentially of a water-soluble molecularly dehydrated sodium phosphate having a Na_2O/P_2O_5 molecular ratio of from 1:2 to 5:3, each agglomerate being

composed of irregular powder particles of said phosphate loosely adhering to each other to form said agglomerate and having intimately and uniformly interspersed therein from about 7% to about 12% by weight of sodium carbonate and from about 0.1% to about 2% by weight of a water-soluble wetting agent selected from the group consisting of alkylated aromatic sulfonates, alkyl sulfonates and alkyl sulfates, said agglomerates being characterized by having a substantially higher rate of solution than a mixture consisting of said sodium phosphate and said sodium carbonate, in both the agglomerated and unagglomerated form.

2. The product defined in claim 1 wherein the water-soluble molecularly dehydrated sodium phosphate has a Na_2O/P_2O_5 molecular ratio of about 1:1.

3. A water treating product in the form of distinct highly porous agglomerates of sodium hexametaphosphate, each agglomerate being composed of irregular powder particles of said phosphate loosely adhering to each other to form said agglomerate and having intimately and uniformly interspersed therein from 7% to 12% by weight of sodium carbonate and from 0.1% to 2% by weight of a sodium salt of an alkylated aromatic sulfonic acid having 8 to 16 carbon atoms in the alkyl chain, said agglomerates being characterized by having a substantially higher rate of solution than a mixture consisting of said sodium hexametaphosphate and said sodium carbonate, in both the agglomerated and unagglomerated form.

4. The product defined in claim 3 wherein dodecyl benzene sodium sulfonate is the sodium salt of an alkylated aromatic sulfonic acid employed.

5. A water treating product in the form of distinct highly porous agglomerates consisting essentially of 90.82% by weight of sodium hexametaphosphate, 8.97% by weight of sodium carbonate and 0.2% by weight of sodium oleyl sulfate, each agglomerate being composed of irregular powder particles of said phosphate loosely adhering to each other to form said agglomerate and having said carbonate and sulfate intimately and uniformly interspersed therein, said agglomerate being characterized by having a substantially higher solution rate than a mixture consisting of said sodium hexametaphosphate and said sodium carbonate, in both the agglomerated and unagglomerated form.

6. A water treating product in the form of distinct highly porous agglomerates containing 91% by weight of sodium hexametaphosphate, 8.5% by weight of sodium carbonate and 0.5% by weight of sodium lauryl sulfate, each agglomerate being composed of irregular powder particles of said phosphate loosely adhering to each other to form said agglomerate and having said carbonate and said sulfate intimately and uniformly interspersed therein, said agglomerate being characterized by having a substantially higher rate of solution than a mixture consisting of said sodium hexametaphosphate and sodium carbonate, in both the agglomerated and unagglomerated form.

7. An article of manufacture, a "self-dissolving" water treating product in the form of cubes, tablets, and the like composed of highly porous agglomerates consisting essentially of a water soluble molecularly dehydrated sodium phosphate having a Na_2O/P_2O_5 molecular ratio of from 1:2 to 5:3, said product having intimately and uniformly interspersed therein from 7% to 12% by weight of sodium carbonate and from about 0.1% to about 2% by weight of a wetting agent selected from the

11

group consisting of alkylated aromatic sulfonates, alkyl sulfonates and alkyl sulfates, and said product, when added to water, being characterized by the property of having a substantially higher solution rate than a mixture consisting of said sodium phosphate and said sodium carbonate, in both the agglomerated and unagglomerated form, and also by the property of slowly and uniformly liberating carbon dioxide, whereby convection currents are set up in the water which circulate and float said product until it is substantially completely dissolved therein.

8. As an article of manufacture, a "self-dissolving" water treating product in the form of cubes, tablets, and the like composed of highly porous agglomerates consisting essentially of a water soluble molecularly dehydrated sodium phosphate having a $\text{Na}_2\text{O}/\text{P}_2\text{O}_5$ molecular ratio of about 1:1, said product having intimately and uniformly interspersed therein from 7% to 12% by weight of sodium carbonate and from about 0.1% to about 2% by weight of a wetting agent selected from the group consisting of alkylated aromatic sulfonates, alkyl sulfonates and alkyl sulfates, and said product, when added to water, being characterized by the property of having a substantially higher solution rate than a mixture consisting of said sodium phosphate and said sodium carbonate, in both the agglomerated and unagglomerated form, and also by the property of slowly and uniformly liberating carbon dioxide, whereby convection currents are set up in the water which circulate and float said product until it is substantially completely dissolved.

9. The method of producing an agglomerated water treating product, which comprises preparing a substantially dry and homogeneous mixture consisting essentially of a water-soluble molecularly dehydrated sodium phosphate having a particle size of less than 80 mesh and a $\text{Na}_2\text{O}/\text{P}_2\text{O}_5$ molecular ratio of from 1:2 to 5:3 together with from 0.1% to 2% by weight of a water-soluble wetting agent selected from the group consisting of alkylated aromatic sulfonates, alkyl sulfonates, and alkyl sulfates and also a sufficient amount of hydrated sodium carbonate having from about 30% to about 40% water of hydration to supply a water content of from 3% to 6% by weight of the substantially dry mixture, thereupon subjecting said substantially dry mixture to an agglomerating treatment which consists in agitating said mixture to liberate water of hydration from said hydrated salt whereby agglomerates are formed and thereafter drying said agglomerates to produce a product characterized by having a substantially higher solution rate than a mixture consisting of said sodium phosphate and said sodium carbonate, in both the agglomerated and unagglomerated form.

10. The method of producing an agglomerated water treating product, which comprises preparing a substantially dry and homogeneous mixture consisting essentially of a water-soluble molecularly dehydrated sodium phosphate having a particle size of less than 80 mesh and a $\text{Na}_2\text{O}/\text{P}_2\text{O}_5$ molecular ratio of from 1:2 to 5:3 together with from 0.1% to 2% by weight of a water-soluble wetting agent selected from the group

12

consisting of alkylated aromatic sulfonates, alkyl sulfonates and alkyl sulfates and also a sufficient amount of hydrated sodium carbonate having from 30% to 40% water of the hydration to supply a water content of from 3% to 6% by weight of the substantially dry mixture, subjecting said substantially dry mixture to an agglomerating treatment which consists in agitating said mixture to liberate water of hydration from said hydrated salt whereby agglomerates are produced, forming a layer of agglomerates, heating said layer to form a unitary sheet, subdividing said sheet into detachable sections and thereupon drying said subdivided sheet to yield a product characterized by having a substantially higher solution rate than a mixture consisting of said sodium phosphate and said sodium carbonate, in both the agglomerated and unagglomerated form.

11. The method defined in claim 10 in which the water soluble molecularly dehydrated sodium phosphate has a $\text{Na}_2\text{O}/\text{P}_2\text{O}_5$ molecular ratio of about 1:1.

12. The method defined in claim 10 in which the water soluble molecularly dehydrated sodium phosphate has a $\text{Na}_2\text{O}/\text{P}_2\text{O}_5$ molecular ratio of about 6:5.

13. The method defined in claim 10 in which the water soluble molecularly dehydrated sodium phosphate has a $\text{Na}_2\text{O}/\text{P}_2\text{O}_5$ molecular ratio of about 5:3.

14. The method of producing an agglomerated water treating product, which comprises mixing together 9 parts by weight of dry soda ash and an aqueous solution of 2 parts of dodecylbenzene sodium sulfonate in 6 parts of water until the mixture begins to granulate and dry out, intimately mixing 89 parts by weight of -80 mesh sodium hexametaphosphate with the resulting product to form agglomerates therewith, passing the agglomerates through a 12 mesh screen, drying the screened agglomerates in a $\frac{1}{4}$ inch layer for 30 to 45 minutes with circulating air at 80° to 90° C. and then rescreening the dried material to yield from 90% to 95% of -12 +80 mesh agglomerates which are characterized by having a substantially higher solution rate than a mixture consisting of said sodium hexametaphosphate and said sodium carbonate, in both the agglomerated and unagglomerated form.

106,470	Australia	Jan. 20, 1939

Certificate of Correction

July 26, 1949

Patent No. 2,477,492

JOE E. MOOSE

It is hereby certified that errors appear in the printed specification of the above numbered patent requiring correction as follows:

Column 6, line 23, for "30 to 40" read 30 to 45; column 10, line 53, for the word "containing" read *consisting essentially of*;

and that the said Letters Patent should be read with these corrections therein that the same may conform to the record of the case in the Patent Office.

Signed and sealed this 27th day of December, A. D. 1949.

[SEAL]

THOMAS F. MURPHY,
Assistant Commissioner of Patents.
